CLAIM

(22) Filed: **Jul. 6, 2011**

The ornamental design for a control device for a vehicle dynamics control system, as shown and described.

(30) **Foreign Application Priority Data**

DESCRIPTION

May 3, 2011 (EM) 001273882-0001

FIG. 1 is a top, front, right side perspective view of a control device for a vehicle dynamics control system showing the new design;

(51) **LOC (9) Cl.** **15-01**

FIG. 2 is a top plan view thereof;

(52) **U.S. Cl.**

FIG. 3 is a front elevational view thereof;

USPC **D15/5**

FIG. 4 is a left side elevational view thereof;

(58) **Field of Classification Search**

FIG. 5 is a right side elevational view thereof;

USPC D15/1, 3, 5; D13/112, 101, 113, 114,
D13/199; 280/455.1; 701/38

FIG. 6 is a rear elevational view thereof; and,

See application file for complete search history.

FIG. 7 is a bottom plan view thereof.

(56) **References Cited**

The portions of the design depicted in broken lines form no part of the claimed design.
